UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

INDUCTANCE SYSTEM

Application filed June 5, 1929. Serial No. 368,692.

My invention relates broadly to frequency changing systems, and more particularly to inductance systems employed in frequency changing systems.

5 One of the objects of my invention is to provide an efficient and easily manipulated inductance system for high frequency transmission systems.

Another object of my invention is to provide an efficient artificially cooled inductance system for high frequency transmission systems.

Still another object of my invention is to provide in a high frequency signaling system, an inductance arrangement in which a circulating liquid cooling medium is employed for maintaining the inductance arrangement at normal temperatures.

A further object of my invention is to 20 provide an artificially cooled inductance system having a plurality of inductance units associated therewith in which connections between each of the inductance units and a reservoir of circulating cooling medium are 25 provided for the inductance units substantially at or near the electrical centers thereof.

A still further object of my invention is to provide an artificially cooled inductance 30 system having a plurality of inductance units made up of concentrically disposed coiled tubes in which connections between the tubes of each of the inductance units and a reservoir of circulating cooling medium 35 are provided for the inductance units substantially at or near the electrical centers thereof.

Other and further objects and features 40 of my invention will be apparent to those skilled in the art to which this invention relates from the following specification and the appended drawings.

It is an object of my invention to provide a tube, disposed within the main or 45 outer tube of the inductance, for the flow in

one direction of the circulating cooling medium and to provide connections of preferably flexible tubing material, such as rubber tubing, for the inner tube and the outer tube of the inductance unit at places on the 50 inductance where the magnitude of the high frequency voltage is a very low or minimum value. Where the inductance system of my invention is employed in a balanced or push pull electron discharge device circuit arrangement the place of minimum or substantially minimum magnitude of high frequency voltage is normally at or near the center of the inductance unit.

According to my invention an inductance 60 system adapted for artificial cooling through the action of a circulating cooling medium is provided with a plurality of inductance units each made up of coiled tubes through which the circulating cooling medium is 65 passed. Provision is also made for connecting certain of the inductance units into the circuits of a signaling system when certain operating conditions are to be attained and other inductance units when other operating 70 conditions are desired. Flexible connections, made of material such as rubber tubing, are provided between the inductance units and the cooling medium reservoir. Ordinarily rubber tubing is not a very good 75 insulator for high frequency currents. It is therefore undesirable to connect the rubber tubing to an inductance unit, employed in a signaling system, at a place on the unit where a high frequency voltage of substantial 80 magnitude exists. It is furthermore impractical to connect the rubber tubing to points on the inductance unit where high frequency voltages of large magnitude exist because the liquid cooling medium, such as 85 water, which is usually employed, while being a good insulator when pure is usually a good conductor when impure. Where impurities, such as dissolved metal salts,

90 pieces of carbonized rubber and the like,

are present in the liquid cooling medium, the cooling medium becomes a fairly good conductor and the rubber tubing connections to the inductance unit introduce additional losses into the circuit.

Referring to the drawings, Figure 1 illustrates an embodiment of my invention; Fig. 2 is a cross-sectional view along line 2-2 of Fig. 1; Fig. 3 is a detail view in broken cross-section of an inductance unit embodying my invention; Fig. 4 is a view in fragmentary section of the inductance unit and Fig. 5 is a cross-sectional view along line 5-5 of Fig. 3.

In Fig. 1 reference numeral 1 designates a rotatable frame member having cross-pieces 2, 3, 4 and 5 supported by end pieces 9 and 10 which are provided with radiating arms for engaging certain of the cross pieces. The rotatable frame member 1 is made of insulating material, such as, synthetic porcelain, wax impregnated dried wood, or the like. A shaft 6 is centrally disposed between the end pieces 9 and 10 which are fixedly attached thereto. Upright members 7 and 8 are positioned upon the panel 11 for supporting the shaft 6 in rotatable position. A handle 12 or similar member, such as a dial or knob which may be readily engaged by the hand of the operator, is mounted upon the shaft 6. Inductance units 13, 14, 15 and 16 comprising helically coiled metallic tubing are mounted upon the cross-pieces 2, 3, 4 and 5, respectively. A bar member 17 of insulating material, such as synthetic porcelain, wax impregnated dried wood or the like is supported adjacent to the frame member 1. Pairs of contact members 18, 19, 20 and 21 are positioned on the member 17 in spaced relation for engaging pairs of contacts 22, 23, 24 and 25 associated with the inductance units 13, 14, 15 and 16, respectively.

Rubber tubing connections 26 are provided between the inductance units and a coil of rubber tubing positioned about the shaft 6, as illustrated in Fig. 2. The cooling liquid is caused to pass through a portion of the coil of rubber tubing upon shaft 6 and then through the inductance units successively. By employing a coil of rubber tubing centrally positioned as to the frame 1 upon the shaft 6 the inductance system may be rotated and different inductance units connected into circuits of a signaling system with minimum wear upon the rubber tubing.

In Fig. 3 an end view of one of the inductance units is illustrated in partial cross-section. The outer metallic tube 27, preferably of copper, encloses a metallic tube 29 of smaller diameter. Spacer members 28 are soldered or otherwise affixed to the coiled tubing 29. A space is provided between the inner surface of tube 27 and the outer sur-

face of tube 29 as illustrated in Fig. 5. A cap member 30 is soldered or otherwise fixed to the end of tube 27. The surface of cap member 30 is smoothed to minimize the corona discharge taking place therefrom since the ends of the inductance unit are at a comparatively high radio frequency potential. Both ends of the inductance units are provided with smooth cap members similar to cap 30 in inductance system employed in the balanced or push pull electron discharge device circuit arrangements. Projecting tubes 31 and 32 are soldered, welded or otherwise affixed to the coiled tubes 29 and 27, respectively, as illustrated in Fig. 4.

The circulating cooling medium is caused to enter the tube 31 through a rubber tubing connection attached to this tube and flows through the coiled tube 29. The cooling medium discharges from the end of the tube 29 into the tube 27 and flows through the space between the tube 29 and the tube 27. The surfaces of the tube 27, which carries the major quantity of the high frequency current flowing through the inductance unit, are thus cooled.

While I have described a preferred embodiment of my invention I desire it understood that various modifications thereof may be made without departing from the spirit of my invention and therefore I do not desire to restrict my invention to the exact details set forth in the foregoing specification except in so far as these details are defined by the appended claims.

What I claim as new and desire to secure by Letters Patent of the United States is as follows:

1. In an inductance system the combination of an inductance unit, means for connecting a supply of circulating cooling medium to said inductance unit, said inductance unit comprising concentric helical tubes disposed one over the other.

2. In apparatus of the class described the combination of an inductance unit comprising a plurality of concentric helical tubes disposed one over the other, said helical tubes being subject to uniform heating throughout their length by the passage of current therethrough, and means for connecting a supply of circulating cooling medium to each of said tubes.

3. In an inductance system the combination of an inductance unit comprising tubes disposed one within another, plug members positioned in the respective ends of the outer one of said tubes and spaced from the respective ends of the inner of said tubes, and means for connecting the electrical center of said tubes of said inductance unit and a supply of circulating cooling medium.

4. In an inductance system of the class described the combination of a plurality of inductance units each comprising a plurality

- of tubes disposed one within the other, a rotatable frame whereon said inductance units are mounted about a common axis, and liquid conducting members for connecting a supply of circulating cooling medium to said inductance units, said liquid conducting members being positioned substantially along said common axis.
5. In an inductance system for currents of radio frequency the combination of a plurality of inductance units each comprising a plurality of tubes disposed one within the other, and means for connecting a supply of circulating cooling medium to each 10 of said tubes at places of low operating radio frequency potential.
6. In an inductance system of the class described the combination of a plurality of inductance units, a rotatable frame member 20 for supporting said inductance units, each of said inductance units comprising a plurality of tubes disposed one within the other, and means for connecting a supply of circulating cooling medium to said inductance 25 units, said inductance units having contacts for engaging stationary contacts supported adjacent to said frame member.
7. In an inductance system for radio frequency currents, a plurality of inductance 30 units each comprising a pair of concentric tubes one surrounding the other, a rotatable frame having lateral members whereon said inductance units are symmetrically mounted about a common axis, plug members closing each end of the outer tube of each of said inductance units, each end of the inner tube of each of said inductance units being open and spaced from its respective adjacent plug, liquid conducting 35 members connected to intermediate points of each of said inductance units for conducting cooling liquid to one of said tubes and away from the other of said tubes, said inductance units being electrically insulated 40 from each other, and means for selectively connecting each of said inductance units with an external circuit.
8. In an inductance system for radio frequency currents, a plurality of inductance 45 units each comprising a pair of concentric tubes one surrounding the other, a rotatable frame having lateral members whereon said inductance units are symmetrically mounted about a common axis, plug members closing each end of the outer tube of each of said inductance units, each end of the inner tube of each of said inductance units being open and spaced from its respective adjacent plug, liquid conducting members connected 50 to intermediate points of each of said inductance units for conducting cooling liquid to one of said tubes and away from the other of said tubes, said inductance units being electrically insulated from each other, and means for selectively connecting each of said inductance units with an external circuit.
9. In an inductance system for radio frequency currents, a plurality of inductance units each comprising a pair of concentric tubes one surrounding the other, a rotatable frame having lateral members whereon said inductance units are symmetrically mounted about a common axis, plug members closing each end of the outer tube of each of said inductance units, each end of the inner tube of each of said inductance units being open and spaced from its respective adjacent plug, liquid conducting members connected to each of said inductance units substantially at the mid-point thereof for conducting cooling liquid to one of said tubes and away from the other of said tubes, said inductance units being electrically insulated from each other, and means for selectively connecting each of said inductance units with an external circuit.
10. In an inductance system for radio frequency currents, a plurality of inductance units each comprising a pair of concentric tubes one surrounding the other, a rotatable frame having lateral members whereon said inductance units are symmetrically mounted about a common axis, plug members closing each end of the outer tube of each of said inductance units, each end of the inner tube of each of said inductance units being open and spaced from its respective adjacent plug, liquid conducting members connected to each of said inductance units substantially at the point of minimum radio frequency potential thereof for conducting cooling liquid to one of said tubes and away from the other of said tubes, said inductance units being electrically insulated from each other, and means for selectively connecting each of said inductance units with an external circuit.
11. In an inductance system for radio frequency currents, a plurality of inductance units having different values of inductance each comprising a pair of concentric tubes one surrounding the other, a rotatable frame having lateral members whereon said inductance units are symmetrically mounted about a common axis, plug members closing each end of the outer tube of each of said inductance units, each end of the inner tube of each of said inductance units being open and spaced from its respective adjacent plug, liquid conducting members connected to intermediate points of each of said inductance units for conducting cooling liquid to one of said tubes and away from the other of said tubes, said inductance units being electrically insulated from each other, and means for selectively connecting each of said inductance units with an external circuit.

of said inductance units with an external circuit.

12. In an inductance system, a pair of concentric tubular members one surrounding the other, and inlet and outlet flow connections for said tubular members substantially at the points of minimum potential thereof, said tubular members being provided with flow-controlling stops whereby cooling liquid delivered to said inlet connection flows continuously through said tubular members to said outlet connection.
